UNITED STATES PATENT OFFICE.

FREDRICK MARGGRAFF, OF AUGUSTA, KENTUCKY, ASSIGNOR TO THE F. A. NEIDER COMPANY, OF AUGUSTA, KENTUCKY, A CORPORATION OF KENTUCKY.

MACHINE FOR FORMING BLANKS FOR TUFTING-BUTTONS.

SPECIFICATION forming part of Letters Patent No. 780,570, dated January 24, 1905.

Application filed September 12, 1902. Serial No. 123,067.

To all whom it may concern:

Be it known that I, FREDRICK MARGGRAFF, a citizen of the United States of America, and a resident of Augusta, county of Bracken, State 5 of Kentucky, have invented certain new and useful Improvements in Machines for Forming Blanks for Tufting-Buttons, of which the following is a specification.

The object of my invention is a means which 10 operating upon a flat blank with prongs projecting from the sides thereof at a single operation cuts the prongs into the back and turns them at an angle thereto without drawing or weakening the metal at the base of the 15 prongs.

In the drawings forming part of this specification, Figure 1 is a plan view of the machine embodying my invention, taken upon line *v v* of Fig. 2. Fig. 2 is a vertical longitudinal sectional view of the same, taken upon line *z z* of Fig. 1. Fig. 3 is a transverse sectional view of the same, taken upon line *w w* of Fig. 1. Fig. 4 is a detail perspective view of one of the rollers which are mounted in the 20 female die. Fig. 5 is a plan view of one of the blanks before it has been operated upon by the machine embodying my invention. Fig. 6 is a perspective view of the blank after it has passed through my machine.

Referring to the parts, which are indicated by similar reference-letters wherever they occur throughout the various views, female die A has formed therein a longitudinal vertical way the central portion *a* of which is of 30 the same shape in horizontal section as the central part B of the blank which is fed through the machine, and upon each side of the portions *a* are narrow portions *a' a'* in longitudinal alinement with each other.

Mounted in die A are two rollers, each of 35 which consists of a disk C and a shaft *c*, the shafts and the disks being preferably formed integral. The rollers are mounted in the die, with the disk C in the portions *a' a'* and at a 40 distance apart equal to the distance between the outer faces of the prongs *b b'* of the tufting-button blank as it comes from my machine.

The shafts *c* are journaled in the die A, so as to be readily rotatable therein. I prefer to make the die in two parts each having horizontal perforations to receive the shafts *c*, the parts being held together by pins *a³ a⁴* after the rollers have been placed in position. Upon top of the die a retainer-plate A' is placed, which has a central perforation *a⁵* of 50 the same contour as the blank which is fed to the machine, as shown in Fig. 5. The blank is laid in perforation *a⁵*, and then punch D descends to carry it downward through the die. Punch D has upon its sides vertical 55 grooves *d d'* of a width slightly greater than that of disk C. Grooves *d d'* are in longitudinal alinement with each other and have left between them a partition *d²* of a width equal to the distance between the disks mounted 60 in the die A less twice the thickness of the metal in the blank. When the punch D descends, the rollers C, acting in conjunction 65 with the punch, cut the prongs *b b'* at their base into the central portion B of the blank 70 which forms the back of the button, and the rollers in conjunction with the partition *d²* turn the prongs upward at a right angle to the back, as shown in Fig. 6. The blank is then in shape to receive the cap which will 75 put it in shape for the market. While in operation the rollers rotate, so that the metal is not drawn at the base of the prongs, but retains its original thickness. The metal at the base of the prongs is likewise not subjected 80 to any great pressure and its molecules are not disturbed. The metal, therefore, at the base of the prongs is with my machine in no manner weakened. This is a great desideratum in tufting-buttons, since the part of the 85 prong which is subjected to the greatest strain is its base.

I have shown my invention in the simplest form that is known to me, and it is obvious that many mere mechanical changes might be 90 made therein without departing from the spirit or scope of my invention; and I therefore do not wish to be limited to the details shown; but

What I do claim is—

1. A machine for forming blanks for tufting-buttons consisting of a die, rotating disks mounted therein, a punch having grooves upon its sides to pass the disks whereby when the punch descends the base of the prongs are cut into the blank and the prongs bent upward at an angle with the back substantially as shown and described.
2. In a machine for forming tufting-buttons from blanks the combination of a female die having a way therein, the central portion of

which is similar in shape to the back of the blank, rollers mounted in the die and projecting into the way at diametrically opposite sides thereof, and a punch whose cross-section is similar in outline to the passage formed by the way and the rollers to pass down through said passage.

FREDRICK MARGGRAFF.
